(57) **CLAIM**

The ornamental design for a timing chain guide, as shown and described.

DESCRIPTION

FIG. 1 is a front-outboard perspective view of a timing chain guide showing my new design;

FIG. 2 is a rear-outboard perspective view thereof;

FIG. 3 is a front-inboard perspective view thereof;

FIG. 4 is a rear-inboard perspective view thereof;

FIG. 5 is an outboard side elevation view thereof;

FIG. 6 is an inboard side elevation view thereof;

FIG. 7 is an end elevation view thereof;

FIG. 8 is an opposite end elevation view thereof;

FIG. 9 is a front elevation view thereof; and,

FIG. 10 is a rear elevation view thereof.
